UNITED STATES PATENT OFFICE.

JOHN T. SCHAAFF, OF WASHINGTON, DISTRICT OF COLUMBIA, ASSIGNOR TO THE TABULATING MACHINE COMPANY, OF NEW YORK, N. Y., A CORPORATION OF NEW JERSEY.

STRIPING DEVICE.

Application filed November 6, 1923. Serial No. 673,136.

In the tabulating machine art use is made of so-called tabulating cards which are provided with a number of printed index point designations which are afterwards suitably 5 perforated to receive desired data.

In the use of these cards it is occasionally necessary to distinguish certain cards from others and for this purpose the cards have been differently colored. Such coloring necessitates the use of different paper stock and increases the expense of the cards. According to the present invention such tabulating cards are striped at one edge with a band of color and the balance of the card is left the 10 same as with the usual record cards. The striping of such a band of color upon cards introduces a number of problems among which may be mentioned the increased cost of the striping operation, and the possibility of 15 excess quantities of ink being applied to the card in stock, thereby making them unsightly.

The present invention is directed to the provision of a simple striping attachment or appliance which may be readily attached to the card printing members whereby the striping operation may be performed during the 20 passage of the card stock through the press.

One of the objects of the present invention 25 is the provision of a striping device and appliance which may be readily manipulated by an unskilled laborer with a minimum of danger of damaging the cards in the stock.

Second, the provision of a striping device 30 which may be readily swung to an inoperative position when it is desired to pass cards through the machine which are not to be striped.

Third, the provision of a striping device 35 which will permit the ready changes of inks so that different colored cards may be produced without the expenditure of excessive time in changing from one ink to another.

A still further object of the present invention resides in the provision of certain improvements in construction in the striping of cards to admit various adjustments thereby improving the resulting card product and permitting the use of comparatively unskilled operators upon the card presses.

In the drawings,

Fig. 1 shows a side elevation of the inking attachment associated with a web of stock which is to be inked.

Fig. 2 is a detail view of the inking attachment displaced to inoperative position. 55

Fig. 3 is a detail sectional view taken on line 3—3 of Fig. 2.

Fig. 4 is another detail sectional view taken on line 4—4 of Fig. 2.

Fig. 5 is a top plan view of the device with the supply reservoir removed.

Fig. 6 is a view of a simple card with the edge striped.

In more detail, 10 designates one of the frame members of the press to which is secured an angle member 11. The location of this angle member is such that the web of card or paper stock to be striped passes adjacent it, as indicated at 12 in Fig. 1. Attached to the angle 11 by suitable screws is a base plate 13. This base plate is preferably slotted at the sides of the screws to permit the disengagement of the plate and the parts mounted on it as a unit by loosening the screw, but without removing the screws from member 11. Fixed to the plate 13 in any desired manner is a suitable bracket 14 which supports a supply reservoir 15. The supply reservoir is preferably removable by loosening a clamping screw 16. Also adjustably fixed to the base plate is a sub-base plate 18 (Fig. 5) which is preferably secured to the base plate by the wing nut 19 which engages a threaded stud projecting through a slot on the base plate. The sub-base plate 18 carries an extended bracket 20 which rotatably supports an adjusting screw 21 having a threaded end engaging a frame member 22. Frame member 22 is slidably adjustable to the right and left relative to the sub-base plate by adjusting the screw 21. The member 22 is properly guided for this sliding movement by a stud 23 which checks into an elongated slot in the sub-base plate. Member 22 has integral with it a supplementary side plate 24 which is slotted, as shown at 25 (Fig. 1), to receive a stud 26 which is fixedly carried by the side plate 27 of the ink fountain assembly. Plate 24 likewise carries a fixed stud 28 on which is rotatably mounted an eccentric 29 fixedly secured to an adjusting lever 30 provided with an operating handle 30'. The eccentric 29 checks into a slot 31 of plate 27 and by adjusting the lever 30 up or down against its limited stops 31^a the plate 27 may be rocked about stud 26 as a pivot. Preferably, the stops 31^a are so placed that

when the device is raised to inoperative position as in Fig. 2, the lever 30 with cam 29 may turn slightly past dead center so as to be held in such position by the weight of the parts.

The slot connection 25 permits the ink fountain devices, which will be hereinafter described, to be entirely removed from the machine at will. When such removal is desired, a latch or pawl 32 is displaced clockwise from the position shown in Fig. 1 thereby permitting plate 27 to be slid to the right until stud 26 is clear of the end of the slot 25 and supporting plate 24. Thereafter the entire assemblage of parts carried by plate 27 can be removed. The construction just described also provides for an adjustment of the striping device from operative to inoperative position as will hereinafter be described.

The construction of the ink fountain and striping devices probably can be best understood from Figs. 2, 3 and 4. Suitably fixed to plate 27 is a substantially rectangular box 33. Fixed to this box at the lower end thereof is a depending member 34 which serves as a lower support for the inking felt 35. Member 34 is curved downwardly and serves to carry off any excess ink from the felt 35 into a cupped depression 36 from which the excess ink may flow into a drain-off receptacle 38 disposed to the left of the box 33. Box 33 is also provided with an overflow opening 39 which leads directly into the receptacle 38, as shown in Figs. 2 and 4. The felt 35 is retained in position in the box 33 by means of a pivoted presser member 40. The amount of ink passing through the felt 35 from the rear of the tank 33 is controlled by an adjustment screw 41 which bears upon a block carried by the presser member 40. The drain box 38 delivers all excess ink through a duct 42 to a box 43 which is suitably supported upon the main frame of the machine and provided with an opening extending into a suitable overflow receptacle 44.

To supply ink in measured amounts to the ink box siphon conduit 45 is provided which has one end extending into a receptacle 15 and the other extending adjacent the top of the rear of the ink box where it is provided with a stop cock 46. To start the flow of ink through the siphon a compressible bulb may be provided by which pressure may be pumped through tube A' into the receptacle 15 above the ink therein. This pressure forces the ink up through the siphon and the amount of flow into the receptacle may be controlled by suitably adjusting the stop cock 46. However, when a bulb is used to supply the starting pressure, if the bulb is suddenly released it tends to draw a vacuum in the receptacle and thus stop the flow. A preferable way of starting the flow, there-

fore, is for the operator to have a rubber tube AA which he can slide over tube A' and blow into the receptacle. A vent hole 48 may be provided in the top of the receptacle. This hole, however, is preferably small enough to permit the creation within the receptacle of sufficient pressure to start the flow through the siphon. The vent insures a continuation of the flow after it has started. After the siphon begins to operate the flow of ink may be stopped and started by turning valve 46 until the receptacle is empty.

Preferably a slight excess of ink is fed to the ink receptacle and the excess is permitted to drain off through the opening 39. To adjust the device into operative relation with the web of paper stock which is to be inked the handle 30 is thrown into the position shown in Fig. 1 thereby bringing the inking felt against the paper to be striped. After the ink box assembly is thus placed into operative position the felt is adjusted against the strip of paper by manipulating thumb screw 21, which displaces the entire ink box assembly laterally with respect to the paper web. Subsequently the amount of ink which is to be applied to the paper can be controlled by adjusting the screw 41 which controls the amount of ink fed through the felt wicking. Any excess ink passing through the felt drains into the receptacle 36 and is thus prevented from dropping on the paper. During periods when the press is shut down if it is desirable to displace the whole ink fountain to the inoperative position, i. e., that shown in Fig. 2, this is done by a counterclockwise adjustment of the eccentric lever 30. During such times any excess ink from felt 35 or excess ink from the siphon will be properly drained back into the overflow receptacle 38. The drain opening 39 should be so positioned that its lower edge will be slightly below the level of the highest part of member 34 when the apparatus is tilted to inoperative position as in Fig. 2. This will permit excess ink to flow through said opening instead of over member 34.

If at any time it is desired to change from one ink to another for the purpose of changing the color or for any other reason the entire ink fountain assembly may be removed from the sub-base plate. This is effected by properly adjusting the eccentric, swinging latch 32 clockwise, thereafter displacing the ink fountain assembly to the right until stud 26 is clear of the end of its retaining slot 25.

What I claim is:

1. An apparatus for coloring stock in its passage through a printing machine and comprising in combination, a color-applying device comprising a unitary structure consisting of a reservoir for coloring matter and means for extracting the coloring matter therefrom and applying it to the stock, means for supporting said device in a position to engage and

- apply coloring material to the moving stock, means for adjustably setting said device in any desired relation to the path of movement of the stock, means for supplying coloring material to said device, and means for conducting excess coloring matter from said device and away from the moving stock. 5
2. An apparatus for coloring stock in its passage through a printing machine and comprising in combination, a color-applying device comprising a unitary structure consisting of a reservoir for coloring matter and means for extracting coloring matter therefrom and applying it to the stock, means for supporting said device to engage and apply coloring material to the moving stock, means for adjusting said device toward and away from the path of movement of the stock, independent means for moving said device from operative to inoperative position at will and vice versa with respect to the moving stock, and means for supplying coloring material to said device. 10
3. An apparatus for coloring stock in its passage through a printing machine and comprising in combination, a color-applying device comprising a unitary structure consisting of a reservoir for coloring matter and means for extracting coloring matter therefrom and applying it to the stock, means for supporting said device to engage and apply coloring material to the moving stock, means for adjusting said device toward and away from the path of movement of the stock, independent means for moving said device from operative to inoperative position at will and vice versa with respect to the moving stock, and means for supplying coloring material to said device. 15
4. An apparatus for coloring stock in its passage through a printing machine and comprising in combination, a color-applying device, means for supporting said device in a position to engage and apply coloring material to the moving stock, means for supplying coloring material to said device, means for regulating the supply of coloring material from said device and away from the moving stock. 20
5. An apparatus for coloring stock in its passage through a printing machine and comprising in combination, a color-applying device including a wick, means for supporting said device in a position to apply coloring material to the moving stock, means for adjusting said device toward and away from the path of movement of the stock including an operating handle, means to limit the movement of the handle in either direction, means for supplying coloring material to said device, and means for varying the cross-section of said wick. 25
6. An apparatus for coloring stock in its
- passage through a printing machine and comprising in combination, a color-applying device, means for supporting said device to engage and apply coloring material to the moving stock, means for adjusting said device toward and away from the path of movement of the stock, independent means for moving said device from operative to inoperative position at will and vice versa with respect to the moving stock, an auxiliary reservoir for supplying coloring material to said device, a main reservoir for supplying coloring material to said auxiliary reservoir, and means whereby said auxiliary reservoir and device may be detached from the apparatus. 30
7. An apparatus for coloring stock in its passage through a printing machine and comprising in combination, a liquid-conducting, color-applying device, means for supporting said device to engage and apply coloring material to the moving stock, means for adjusting said device toward and away from the path of movement of the stock, independent means for moving said device from operative to inoperative position and vice versa with respect to the moving stock, an auxiliary reservoir for supplying coloring material to said device, a main reservoir for supplying coloring material to said auxiliary reservoir, and means for varying the cross-section of said device. 35
8. An apparatus for coloring stock in its passage through a printing machine comprising a unitary device consisting of a reservoir for coloring matter and means for extracting coloring matter therefrom and applying it to moving stock, means for adjusting said device to and from the path of movement of the stock and means for adjusting said device transversely to the path of movement of said stock. 40
9. An apparatus for coloring stock in its passage through a printing machine comprising a unitary device consisting of a reservoir for coloring matter and means for extracting coloring matter therefrom and applying it to moving stock, means for adjusting said device to and from the path of movement of said stock, means for adjusting said device transversely to the path of movement of said stock and independent means for moving said device from operative to inoperative position at will with respect to the stock. 45
10. An apparatus for coloring stock in its passage through a printing machine comprising a unitary device consisting of a reservoir for coloring matter and means for extracting coloring matter therefrom and applying it to moving stock and means for conducting excess coloring matter from said device and away from the moving stock. 50

In testimony whereof I hereto affix my signature.

JOHN T. SCHAAFF.
